UNITED STATES PATENT OFFICE.

JOSEPH WENCIL HRUSKA, OF MANKATO, MINNESOTA.

ROAD DRAG.

1,406,019.

Specification of Letters Patent.

Patented Feb. 7, 1922.

Application filed December 16, 1920. Serial No. 431,209.

To all whom it may concern:

Be it known that I, JOSEPH W. HRUSKA, a citizen of the United States, residing at Mankato, in the county of Blue Earth and 5 State of Minnesota, have invented certain new and useful Improvements in Road Drags; and I do declare the following to be a full, clear, and exact description of the invention, such as will enable others skilled 10 in the art to which it appertains to make and use the same.

My invention relates to improvements in road drags or planers and has for its principal object to provide a device of this character which may be easily and inexpensively constructed entirely of I-beams and channel bars, secured together by common bolts which enable the machine to be easily assembled by unskilled labor, permitting it to be shipped 20 or transported from place to place in a knocked down condition, the arrangement of bars being such that the drag is absolutely rigid when assembled.

Another object is to provide a road planer 25 which embodies a runner and both a main and a supplemental scraper bar associated therewith in a novel manner to effectively remove any mounds and other projections in the roadway, deposit some of the earth in 30 the depressions, and discharge the remainder at the center of the highway.

With the foregoing in view, the invention resides in the novel construction and arrangement of parts hereinafter described 35 and claimed, the descriptive matter being supplemented by the accompanying drawings.

Figure 1 is a perspective view of a road planer constructed in accordance with my 40 invention.

Figure 2 is a top plan view.

Figure 3 is a sectional view as indicated by line 3—3 of Fig. 2.

Figure 4 is a detail side elevation showing 45 the manner of forming the front ends of the runner beam and the two scraping beams.

In the drawings above briefly described, the numeral 1 designates an I-beam forming a runner which is adapted to travel along 50 the center of a roadway. Spaced laterally from the I-beam 1 is a second I-beam 2 which diverges forwardly with respect thereto, the front end of said beam 2 being by preference disposed slightly in advance of the beam 1, while the rear end 3 of said beam 2 is spaced directly in rear of the beam 1,

on a line extending longitudinally of the latter, forming an outlet throat 4 for any earth scraped from the surface of the road and not deposited in depressions therein. 60 Between the beams 1 and 2 and disposed in parallel relation with the latter is a third and relatively short I-beam 5 whose rear end is inwardly spaced from the intermediate portion of the I-beam 1 to form an outlet 65 throat 6 for the earth or the like scraped from the roadway by said beam 5.

For connecting the several beams, I preferably employ four transverse channel bars 7, 8, 9 and 10 respectively. The bar 7 ex- 70 tends across the front ends of the three beams 1, 2 and 5 and is secured by bolts or the like 11 thereto; the bar 8 extends from the front end of the beam 1 across the beams 5 and 2, at substantially right angles to the 75 last named beams, and is secured in place by bolts 12; the bar 9 passes from the front end of the beam 1 across the rear end of the intermediate beam 5 to a point near the rear end of the beam 2, and bolts 13 are employed 80 for securing it in place; and the bar 10 is relatively short and connects only the rear end portions of the two beams 1 and 2, bolts 14 being employed for securing these parts together. This arrangement of the bars 7, 85 8, 9 and 10 forms an extremely rigid connecting means for the several longitudinal beams 1, 2 and 5, even though ordinary bolts are used for securing the several parts together, but it will be understood that if it is 90 not desirable to ship or transport the scraper in a knocked down condition, rivets may be substituted for the bolts.

The front ends of the three beams 1, 2 and 5, are preferably beveled as indicated at 95 15 and the bottom flanges 16 of these beams are bent upwardly along the bevel as shown. In forming this construction, the details illustrated in Fig. 4 may be followed. The lower portion of the web 17 is formed with a V-shaped notch 18 whose lower edge is flush with the upper surface of the flange 16, while its upper edge forms the bevel 15. After notching the web 17 in this manner, the flange 16 is bent upwardly along the bevel 100 15 and may be welded or otherwise secured. This forms a simple and inexpensive, yet a highly efficient and desirable manner of constructing the front ends of the several beams, and although this detail is preferably fol- 105 lowed, other adequate constructions could 110 of course be used.

A suitable chain 19 is connected at its ends to the front ends of the beams 1 and 2, and is equipped with an adjustable draft link 20 which may be so positioned along the length 5 of the chain as to cause the runner 1 to travel on a strictly straight line along the center of the roadway. The scraping beam 2 then extends entirely to the edge of the road and this beam, together with the beam 10 5, effectively planes or scrapes the surface of the roadway so that all projecting surfaces are removed and the hollows filled, any of the material which is not deposited in the hollows, being discharged through the throat 4 at the center of the roadway. Attention may here be directed to the fact that the end 3 of beam 2 is directly in rear 15 of the beam 1 so that the throat 4 is elongated longitudinally of the roadway instead 20 of transversely thereof, this being of great advantage in properly depositing the earth or other material at the center. The invention is not only of simple and inexpensive 25 construction, but is economical in operation, since no attendant is required, due to the fact that the drag may be pulled by a tractor, truck or the like and will at all times follow its power. Whenever the device must 30 be carried from one point on a roadway to a rather remote point, it may be easily knocked down, loaded on a motor truck or the like, carried to the desired point, and then again set up with ease. This is also of great 35 advantage in initially shipping the device from the factory at which it is constructed.

By using I-beams and channel bars in the construction of the drag, it is not only extremely rigid but will possess sufficient weight to operate effectively, without the 40 necessity of providing a platform to carry a load to weight the machine down. Furthermore, the metal construction insures

long life, even though subjected to extremely rough use and the flanges of the several longitudinal beams form effective cutting edges 45 to act on the surface of the roadway, without however digging into and impairing the road below the surface.

Since probably the best results may be obtained from the several details disclosed, 50 such details may be followed if desired, but I wish it understood that within the scope of the invention as claimed, numerous minor changes may be made.

I claim:

A road planer comprising an I-beam forming a runner adapted to travel parallel with the edges of a road, a second I-beam forming a scraper diverging forwardly with respect to said runner forming beam, with its rear 60 end spaced directly in rear of said runner forming beam, on a line extending along the latter; a third I-beam forming a second scraper spaced inwardly from and parallel with the first named scraper forming beam 65 with its rear end spaced inwardly from the intermediate portion of said runner forming beam, a channel bar extending across the front ends of the three beams, a second channel bar extending from the front end of the 70 runner forming beam across the other beams at substantially right angles to the latter and secured to all of said beams, a third channel bar extending from the front end of the runner forming beam to a point near the 75 rear end of the first named scraper forming beam and secured to all of the beams, and a relatively short bar connecting the rear end of said runner forming beam with the corresponding end of said first named scraper 80 forming beam.

In testimony whereof I have hereunto set my hand.

JOSEPH WENCIL HRUSKA.
